COMBINED TOILET SEAT AND COVER

Nels L. Olson, Detroit, Mich.

Application April 2, 1945, Serial No. 586,079

2 Claims. (Cl. 4—234)

1

The present invention relates to improvements in combination toilet seats and covers therefor, and more particularly, to a new and useful hinge structure for hingedly connecting the seat and cover to one another as well as to the toilet bowl.

The primary object of the invention is to provide a combined toilet seat and cover therefor which are hingedly connected to the toilet bowl in such a manner as to balance the cover when the seat is in its raised or partly raised positions.

Another object of the invention is to provide a combined toilet seat and cover which are hingedly connected one to the other and to the toilet bowl in such a manner as to maintain the seat in an elevated position and to prevent the same from falling and prevent possible damage to the toilet seat and cover such as breakage and the like.

Another object of the invention is to provide a unique and novel hinge connection for a toilet seat and cover which is slightly offset from the hinge connection of the toilet seat with the toilet bowl so that when the cover is in its raised position and the toilet seat is raised a predetermined angular distance, the weight of the toilet seat cover will exert a downward force on the offset hinge connection and thereby cause the toilet seat to be moved to a raised position.

Other objects and advantages of the invention will become apparent during the following description of the accompanying drawing, wherein:

Figure 1 is a top elevational view of the combined toilet seat and cover illustrating the manner in which the same are hinged together and to the toilet bowl;

Figure 2 is a side elevational view of a combined toilet seat cover further showing the manner in which the same are hingedly connected to the bowl;

Figure 3 is a rear elevational view of the combined toilet seat cover and seat illustrating in detail the arrangement of the various hinge connections and showing the upstanding lugs on the rear portion of the seat to provide hinge leaves for the seat cover; and

Figure 4 is a fragmentary side elevational view of the combined toilet seat and cover showing the cover in its raised position and the manner in which the seat is balanced when in its raised or partly raised position.

In the drawing, the reference character 5 will generally be employed to represent a toilet bowl of conventional construction including a bowl portion 6 and a bead portion 7 extending about the open upper end thereof. The bead portion 7 is

enlarged at the rear of the toilet bowl 5 to provide an extension or platform 8.

The rear extension 8 is provided with a pair of spaced bores 9 for receiving the threaded shank 10 of a hinge bracket 11. The hinge brackets 11 are arranged in spaced relation and are held in place by nuts 12 threaded on the studs 10 of the threaded shank. Rubber or flexible washers 13 may be interposed between the nuts 12 and the under side of the rearwardly extending projection 8 to facilitate the threaded stud and the brackets 11 being drawn tightly in place.

The toilet seat 14 includes an annular body portion 15 having a rearwardly extending portion 16 which is adapted to project between the hinge brackets 11 so as to be hingedly connected thereto by means of pintle pins 17 received in openings 18 extending inwardly from the side edges of the rear extension 16. Formed on the rearwardly extending portion 16 of the seat cover 15 is a pair of spaced upstanding lugs 19 which are integrated with the toilet seat and may be molded therewith during the construction of the seat. As shown in the drawing, the upstanding lugs 19 are disposed adjacent the side edges of the rearwardly extending portion 16 of the toilet seat and are arranged adjacent the rearmost edge of said rearwardly extending projection.

The upstanding lugs 19 are provided with rearward abutment surfaces 19a and also with aligned bores or openings 20 which are offset rearwardly from the hinge pin 17 (Figure 2) for a purpose which will be hereinafter more fully described.

The toilet seat cover, generally indicated by the reference character 22 includes an ovate body portion 23 having a rearwardly extending projection 24 extending between the upstanding lugs 19 carried by the toilet seat 14. The rearwardly extending portion 24 of the seat cover 23 is provided with a pair of bores 25 extending inwardly to the side edges thereof and adapted to register with the bores 20 in the upstanding lugs 19 for the purpose of receiving hinge pins 26.

Cushion pads or feet 27 and 28 may be provided on the underside of the toilet seat 14 and seat carrier 22 so as to maintain the toilet seat in a level position and to prevent marring or scratching of the finish of the toilet bowl and seat as well as the seat cover when in said lowered position.

It is to be noted that the hinge pins 17 and 26 are vertically offset with the hinge pins 26 positioned slightly rearward of the hinge pins 17. When the toilet seat cover 22 is in its raised posi-

tion, as shown in Figure 4, the weight thereof will be slightly offset from the hinge pin 17 so that when the toilet seat 14 is raised, the force and weight of the toilet cover 22 will be exerted downwardly on the hinge pins 26 rearwardly of the hinge pin 17, so as to counterbalance the weight of the toilet seat 14 and retain the same in a raised position. The cover 22 and seat 14 will then be supported by the engagement of the rearward abutment surfaces 19a of the upstanding lugs 19 with the upper surface of the rearward extension 8 of the toilet bowl 5. As shown in Figure 4, the toilet seat has been indicated in dotted lines as being partly raised to illustrate the manner in which the leverage increases as the toilet seat approaches the vertical position. When the seat and cover are fully raised, the downward force of the seat cover 23 will be exerted on the hinge pins 26 to thereby exert a downward force on the lug 19 carried by the rear portion of the toilet seat and produce a counter-acting force to retain the seat in its raised position. Thus, the seat and seat cover will not be precariously balanced, as is the case in present-day toilet seat and seat cover constructions, so as to be easily tilted forwardly and dropped on the toilet bowl and the resulting damage through said dropping will be eliminated, so as to prolong the life of the toilet bowl as well as the toilet seat and cover.

The toilet seat 14 and seat cover 22 are preferably formed of a plastic material molded to the proper shape under heating pressure and during the molding of the toilet seat, the upstanding lugs 19 are molded as an integral part thereof as shown in the drawing. In certain toilet seat constructions, it may be advisable to use hinge brackets 11 having straight neck portions instead of the goose-neck portions illustrated. When the toilet seat and cover are resting against the front wall of a toilet tank T (Figure 4), the goose-necked type bracket 11 may be used and the seat cover held in its elevated position, with the weight of the cover exerting a downward force on the hinge pin 26 to retain the seat in its raised position. In other types of toilet bowl and seat constructions where the straight-necked brackets are used, such as where the toilet tank T is eliminated, and a flush valve employed, the seat and cover will rest against the wall directly in back of the toilet bowl so that the weight of the cover will exert a downward force on the hinge pins 26 and thereby counterbalance the seat and retain the same in its raised position.

It is to be understood that the form of the invention herewith shown and described is to be taken as a preferred embodiment of the same and that various changes may be made in the shape, size and arrangement of parts without departing from the spirit of the invention or the scope of the subjoined claims.

What I claim is:

1. A combination toilet seat and cover for a toilet bowl comprising a toilet seat having a rearward-extending portion, a pair of hinge brackets

for attachment to the rear portion of said toilet bowl having hinge members hingedly connecting said brackets to said rearwardly-extending portion, a pair of laterally-spaced upstanding projections on said rearwardly-extending portion, a seat cover having a rearwardly-extending member hingedly disposed between said projections, and hinge members hingedly connecting said rearwardly extending member to said projections, said cover hinge members being offset upwardly and rearwardly from said seat hinge members such that a plane passing therethrough is inclined rearwardly when said seat is in its lowered position on said toilet bowl, whereby the weight of said seat cover in its raised position will exert a downwardly-acting counterbalancing force on said seat in a direction rearwardly of its hinge connection to said hinge brackets during the raising of said seat and in the raised position thereof so as to counteract the tendency of said seat to accidentally fall from its raised position.

2. A combination toilet seat and cover for a toilet bowl comprising a toilet seat having a rearwardly-extending portion, a pair of hinge brackets for attachment to the rear portion of said toilet bowl having hinge members hingedly connecting said brackets to said rearwardly-extending portion, a pair of laterally-spaced upstanding projections on said rearwardly-extending portion, a seat cover having a rearwardly-extending member hingedly disposed between said projections, and hinge members hingedly connecting said rearwardly extending member to said projections, said cover hinge members being offset upwardly and rearwardly from said seat hinge members such that a plane passing therethrough is inclined rearwardly when said seat is in its lowered position on said toilet bowl, said upstanding projections having upwardly directed rearwardly disposed abutment surfaces thereon for providing supporting points of engagement of the raised seat with said toilet bowl remote from the hinge connection thereof to said hinge brackets so as to provide a maximum supporting leverage for the weight of said seat and seat cover on said toilet bowl, whereby the weight of said seat cover in its raised position will exert a downwardly-acting counterbalancing force on said seat in a direction rearwardly of its hinge connection to said hinge brackets during the raising of said seat and in the raised position thereof so as to counteract the tendency of said seat to accidentally fall from its raised position.
